CLAIM

The ornamental design for a hemostatic device, as shown and described.

DESCRIPTION

FIG. 1 is a top front perspective view of a hemostatic device, showing our new design;

FIG. 2 is a bottom front perspective view thereof;

FIG. 3 is a front view thereof, the rear view being a mirror image thereof;

FIG. 4 is a right side view thereof;

FIG. 5 is a left side view thereof;

FIG. 6 is a top view thereof;

FIG. 7 is a bottom view thereof;

FIG. 8 is a perspective view thereof showing the balloon in an open state; and,

FIG. 9 is a front view thereof showing the balloon in an open state.

The dash-dash broken lines showing portions of the hemostatic device are for the purpose of illustrating environmental structure and form no part of the claimed design.
